UNITED STATES PATENT OFFICE.

EDWIN W. FULTON, OF LOWVILLE, NEW YORK, ASSIGNOR TO VELOX VISE CO., INC.,
OF LOWVILLE, NEW YORK.

VISE.

1,299,828.

Specification of Letters Patent.

Patented Apr. 8, 1919.

Application filed December 3, 1918. Serial No. 265,120.

To all whom it may concern:

Be it known that I, EDWIN W. FULTON, a citizen of the United States, residing at Lowville, in the county of Lewis and State 5 of New York, have invented certain new and useful Improvements in Vises; and I do hereby declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to new and useful improvements in quick acting bench vises of the type in which a movable jaw is mounted upon a tail block having a sliding movement through a passageway in the 20 stationary jaw and held in an adjusted position by fulcrum means while the work is held in position by an independent action of the movable jaw.

More specifically, the present invention 25 consists of a vise of this type in which an adjustable bearing plate is mounted within the opening through the shank portion of the fixed jaw and upon which the tail block is adapted to rest, and in the provision of 30 fulcrum members for locking the block.

Another feature of the present invention consists in the provision of a novel means 35 of collar for actuating the movable jaw which means is located outside the casing, and which will afford a greater bearing for the movable jaw upon the tail block.

The invention consists of further details 40 of construction, combination and arrangement of parts which will be hereinafter fully described, shown in the accompanying drawings and then specifically defined in the appended claims.

45 My invention is illustrated in the accompanying drawings which, with the numerals of reference marked thereon, form a part of this application, and in which:

Figure 1 is a side elevation of a vise made in accordance with my invention.

50 Fig. 2 is a central longitudinal sectional view through the vise.

Fig. 3 is a cross sectional view on line 3-3 of Fig. 2.

Fig. 4 is a sectional view on line 4-4

of Fig. 1, showing the face view of the collar to which the screw is swiveled, and 55

Fig. 5 is a sectional view on line 5-5 of Fig. 2, showing the adjustable bearing plate on which the tail block is mounted.

Reference now being had to the details of the drawings by numerals:

1 designates the fixed jaw which is provided with apertured flanges through which fastening means is passed to secure the same to a bench or other object, and the shank portion of said jaw is provided with a 60 rectangular opening 3 through which the tail block 4 is adapted to have a sliding movement. The tail block is provided with oppositely disposed longitudinal grooves 5 having beveled walls 6, and one end of the 65 tail block is provided with a hole, the walls of which are threaded for the reception of the screw 7. The wall of the tail block leading into the opening in which said screw is mounted has an oil duct 8, whereby 70 the screw may be conveniently lubricated.

Mounted in recesses 9 having top walls inclined, which recesses are formed opposite each other in the walls of the opening through the shank portion of the fixed jaw 75

are the two fulcrum members, designated by numerals 10, each of which is provided with beveled tops conforming to the inclined top walls of said recesses and beveled surfaces 11 and 12 conforming to the beveled 80 surfaces of the channels in the opposite faces of the tail block, and into which the beveled portions of said members project.

The outer face of each of said fulcrum members is provided with a threaded hole 85 engaged by an adjusting screw 13 mounted in an aperture formed in the wall of the opening through the shank portion of the fixed jaw. The bottom wall of said opening through which the tail block passes is 95

provided with a transverse recess 14, the bottom wall 14' of which is inclined preferably ten degrees and upon which an adjustable bearing plate 15, inclined upon its under edge, is adapted to be supported. Said 100

plate is preferably of a hardened material to withstand the wear incident to the sliding movement of the tail block which rests thereon. Said plate is given a longitudinal movement through the medium of the adjusting screw 15' mounted in a threaded 105

aperture leading through the recess in which the block is mounted.

The head of the screw 7 has a circumferential groove 16 formed therein, adapted to receive a semi-cylindrical rib 18 integral with the segment collar 19 which is fastened by screws or other suitable means to the plate 20, which in turn is fastened to the shank portion of the movable jaw 21. Said plate 20 is apertured to receive a stud bolt 22 having a head 23, and with the inner threaded end tapped into a threaded hole in the adjacent end of the tail block. Said head of the screw is provided with a transverse aperture for the reception of the manipulating bar 25.

In operation, when it is desired to separate or move the jaws toward each other, it may be done by slightly raising the end of the tail block carrying the movable jaw sufficiently to disengage the under beveled faces in the longitudinal grooves of the tail block from contact with the under beveled faces of the fulcrum members, it being understood that the tilting of the tail block is made possible by reason of the fact that the vertical height of the opening in the shank portion of the fixed jaw is slightly greater than the width of the tail block. When the block is tilted it may be slid freely back and forth. After the jaws have been adjusted to receive the work, the end of the tail block carrying the movable jaw may be lowered, and as the beveled portions of the fulcrum members engage the lower beveled faces of the grooves in the tail block, the jaws will be held in adjusted positions, after which the screw may be turned to cause the movable jaw to be actuated to securely clamp and hold the work between the jaws. When it is desired to release the jaws from the work, the screw is loosened, and by repeating the operation of elevating the end of the tail block carrying the movable jaw, the block will slide freely.

By the provision of the adjustable bearing plate upon which the tail block is mounted which plate is moved longitudinally through the medium of the screw mounted in the aperture in the wall of the shank portion of the stationary jaw, the tail block may be raised or lowered and thereby adjusting the front or movable jaw, which is an essential feature of applicant's invention.

By the provision of mounting the collar, which operates the movable jaw when the work in the vise is removed, outside of the casting, a large bearing surface is provided for the movable jaw upon the tail block, and in providing the stud bolt, which is tapped into the end of the tail block and which passes through the plate to which the collar is fastened, a secure means is provided for relieving the sliding jaw of strain which will come upon the stud bolt when the travel of

the sliding jaw is outward or releasing the work between the jaws of the vise.

What I claim to be new is:

1. A vise, comprising a fixed jaw with an opening in the shank portion thereof, a bearing plate in the bottom of the opening, a tail block movable through said opening and resting upon said plate, a fulcrum member mounted upon the shank portion of the fixed jaw, means for supporting said member relatively to the side of the tail block, a movable jaw mounted upon the latter, and means for actuating the movable jaw upon the block. 70

2. A vise, comprising a fixed jaw with an opening in the shank portion thereof, a bearing plate in the bottom of the opening, a tail block movable through said opening and resting upon said plate, a fulcrum member mounted within the opening in the shank portion of the fixed jaw, a screw mounted in the wall of the latter and adjustably supporting said fulcrum member relative to the side of the tail block, a movable jaw mounted upon the latter, and means for actuating the movable jaw upon the block. 75 80

3. A vise, comprising a fixed jaw with an opening in the shank portion thereof, the wall of the opening having a recess therein, a bearing plate mounted in the bottom of the opening, a tail block movable through the opening and resting upon said plate, a fulcrum member mounted within said recess, a screw mounted in the wall of said shank portion and engaging the fulcrum member 95 and adapted to hold the same in relative adjustment with the adjacent wall of the tail block, a movable jaw mounted upon the latter, and means for actuating the movable jaw upon the block. 100 105

4. A vise, comprising a fixed jaw with an opening in the shank portion thereof, a bearing plate mounted in the bottom of the opening, a tail block movable through said opening, resting upon said plate and having a longitudinal channel in its face with a beveled surface, a fulcrum member mounted within said opening and having a beveled edge, a screw mounted in an aperture in the wall of the shank portion of the fixed jaw 115 and engaging said fulcrum member, the beveled edge of said member coöperating with the beveled surface in the channel of the tail block to hold the latter in an adjusted position, a movable jaw mounted upon the tail block, and means for actuating the movable jaw upon the block. 120

5. A vise, comprising a fixed jaw with an opening in the shank portion thereof, the walls of the opening being recessed, a fulcrum block mounted in said recess and having a beveled portion, a screw mounted in an aperture in the wall of the recess and engaging said member, a tail block movable through said opening and having a longi- 125 130

- 5 tudinal channel in the face thereof, said channel having a beveled surface coöperating with the beveled portion of said fulcrum member to hold said tail block in an adjusted position, a movable jaw mounted upon the tail block, and means for actuating the movable jaw upon the block.
6. A vise, comprising a fixed jaw with an opening in the shank portion thereof, the walls of the opening having oppositely disposed recesses therein, fulcrum members mounted one in each of said recesses and each provided with a beveled portion, screws passing through openings in the walls of the recesses and engaging said members, a tail block having longitudinal channels in the opposite faces thereof, portions of the surfaces of said channels being beveled and coöperating with the beveled portions of said members to hold the block in an adjusted position, and a movable jaw mounted upon the tail block, and means for actuating the movable jaw upon the block.
7. A vise, comprising a fixed jaw with an opening in the shank portion thereof, a tail block movable through said opening and provided with a threaded hole in one end, a movable jaw mounted upon said tail block, a screw engaging the threaded hole in the block and having a circumferential groove, and a collar fixed to the shank portion of the movable jaw and having a rib swiveled in said groove.
8. A vise, comprising a fixed jaw with an opening in the shank portion thereof, a tail block movable through said opening and provided with a threaded hole in one end, a movable jaw mounted upon said tail block, a screw engaging the threaded hole in the block and having a head with an annular groove in its circumference, a plate secured to said shank portion of the movable jaw and having an opening through which said head screw passes, and a segment collar fixed to said plate and having a rib swiveled in said groove.
9. A vise, comprising a fixed jaw with an opening in the shank portion thereof, a tail block movable through said opening and provided with a threaded hole in one end, a movable jaw mounted upon said tail block, a screw engaging the threaded hole in the block and having a head with an annular groove in its circumference, a plate secured to said shank portion of the movable jaw and having an opening through which said head screw passes, a segment collar fixed to said plate and having a rib swiveled in said groove, and a stud tapped into the end of the tail block and extending through the aperture in said plate.
10. A vise, comprising a fixed jaw with an opening in the shank portion thereof, a tail block movable through said opening and provided with a threaded hole in one end,
- 15 a movable jaw mounted upon said tail block, a screw engaging the threaded hole in the block and having a head with an annular groove in its circumference, a plate secured to said shank portion of the movable jaw and having an opening through which said screw passes, a segment collar fastened to said plate, and having a semi-cylindrical rib projecting therefrom and swiveled in said groove, and a stud tapped into the end of the tail block, projecting through an aperture in said plate and having a head adapted to limit the movement of the movable jaw relative to the tail block.
11. A vise, comprising a fixed jaw with an opening in the shank portion thereof, a bearing plate mounted in the bottom of the opening, and adjustable means for raising and lowering said plate, a tail block passing through said opening and resting upon said plate, fulcrum means coöperating with the tail block to lock the same in adjusted positions, and a movable jaw mounted upon the tail block, and means for actuating the movable jaw upon said block.
12. A vise, comprising a fixed jaw with an opening in the shank portion thereof, the bottom of said opening having a transverse recess with an inclined bottom, a bearing plate having an inclined edge resting upon the bottom of the recess, a screw mounted in a threaded aperture in the wall of said opening and adapted to bear against said plate, a tail block movable through said opening and resting upon said plate, the opposite faces of the tail block having channel with inclined faces, fulcrum means projecting from the wall of the opening into said channels and coöperating with the inclined faces to hold the block in locked positions, a movable jaw mounted upon the tail block, and means for actuating the movable jaw upon the block.
13. A vise comprising a jaw having an opening therethrough, the bottom of said opening having a transverse recess, with an inclined bottom, a bearing member having a correspondingly inclined bottom resting against the inclined bottom of said recess, and a tail-block passing through said opening and resting on said member.
14. A vise comprising a jaw having an opening therethrough, the bottom of said opening having a transverse recess, with an inclined bottom, a bearing member having a correspondingly inclined bottom resting against the inclined bottom of said recess, a tail-block passing through said opening and resting on said member, and means carried by said jaw for moving said member upward on the inclined bottom of said recess.
15. A vise comprising a jaw having an opening therethrough, the bottom of said opening having a transverse recess, with an inclined bottom, a bearing member having

a correspondingly inclined bottom resting against the inclined bottom of said recess, a tail-block passing through said opening and resting on said member, and a screw carried by said jaw for moving said member upward on the inclined bottom of the recess.

In testimony whereof I hereunto affix my signature in presence of two witnesses.

EDWIN W. FULTON.
